UNITED STATES PATENT OFFICE

JAMES R. HUGHES, OF SOUTH BEND, INDIANA, ASSIGNOR TO THE PIERCE-ARROW
MOTOR CAR COMPANY, OF BUFFALO, NEW YORK, A CORPORATION OF NEW YORK

DESIGN FOR A COMBINED FENDER AND HEAD LAMP CASING FOR VEHICLES

Application filed October 29, 1932. Serial No. 45,639. Term of patent 14 years.

To all whom it may concern:

Be it known that I, JAMES R. HUGHES, a citizen of the United States of America, and resident of South Bend, in the county of St. Joseph and State of Indiana, have invented a new, original, and ornamental Design for a Combined Fender and Headlamp Casing for Vehicles, of which the following is a specification, reference being made to the accompanying drawing, forming a part thereof.

In the drawing, Figure 1 is a perspective

view of the combined fender and headlamp casing for vehicles showing my new design, and Fig. 2 is a perspective view showing the design from a different angle than that illustrated in Fig. 1.

I claim:

The ornamental design for a combined fender and headlamp casing for vehicles substantially as shown.

Signed by me at South Bend, Indiana, this 26 day of October, 1932.

JAMES R. HUGHES.
